INVENTOR.

Albert C. Forte,
BY

Geo. P. Kimmel. ATTORNEY.

UNITED STATES PATENT OFFICE.

ALBERT C. FORTE, OF VIRGINIA, MINNESOTA.

IDENTIFYING RIBBON OR CHECK HOLDER.

Application filed July 9, 1925. Serial No. 42,575.

This invention relates to an identifying ribbon or check holder, and has for its object to provide means, in a manner as herein-after set forth, for fixedly securing the identifying check or ribbon to the garment of a person to prevent the use of the check or ribbon by an unauthorized person, so as to overcome the practice which is so common at dances or amusement resorts, of passing the ribbon or check or a part of the same to some other person to allow him to enter the dance hall or amusement resort, and with the holder so constructed that when once the ribbon or check is fixed to the garment of a person it cannot be removed from the holder without rendering the same of no value.

Further objects of the invention are to provide, in a manner as herein-after set forth, a holder for the purpose referred to, which is simple in its construction and arrangement, strong, durable, thoroughly efficient in its use, conveniently adjusted to fixedly secure the ribbon or check to the garment of a person, and inexpensive to manufacture.

With the foregoing and other objects in view, the invention consists of the novel construction, combination and arrangement of parts, as herein-after more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a cross sectional view of the holder.

Figure 2 is an inverted plan of the retainer section of the form shown in Figure 1.

Figure 3 is a top plan view of the supporting section with the check or ribbon carried thereby.

A holder, in accordance with this invention, comprises a supporting section for an identifying ribbon or holder, and a retaining section for maintaining the ribbon or check on the supporting section.

Referring to the drawing 19 generally indicates the retainer section and 20 the supporting section for the ribbon or check 21.

The section 19 is in the form of a circular button and comprises a body portion which is hollow and formed of a flat closed top 22, a rounded closed side 23 and a dish-shaped

bottom 24 preferably of concavo-convex curvature in cross section. The bottom 24 is provided with a centrally disposed opening and with an integral upstanding frusto-conical sleeve 25 having its inner face registering with the wall of the opening in said bottom. The sleeve 25 is of a length to have its free or inner end arranged substantially in alignment with the lower end of the side 23, to form an appropriate clearance between said end and the inner face of the top 22. The sleeve 25 is arranged completely within the body portion and provides a retaining member coacting with the section 20 for securing the latter to the section 19.

The section 20 comprises a circular base 26 of materially less diameter than the section 19, and extending from the inner face of the base 26, is an integral stem formed of a pair of cylindrical portions 27, 28, the former of greater diameter than the latter and of less diameter than the diameter of the base. The portion 27 is integral with the base 26. The portion 28 is of greater length than the portion 27, and for the major portion of its length, it is slotted at right angles, as at 29, to provide a series of resilient locking arms 30. Each of the arms 30 is provided at its upper end with an outwardly extending and upwardly inclined rib 31 which merges into a head 32 of triangular contour having its outer face curving outwardly and downwardly from its apex towards its base throughout whereby the base of the head will overhang the portion 28, so that the rib 31 can seat against the upper edge of the sleeve 25 whereby the sections 19 and 20 will be connected together to prevent the removal of the check or ribbon 21, as the latter is mounted on the stem between the portion 27 and base 26. The heads, 32 owing to the like curvature of their outer faces provide when forced together a puncturing or piercing element for the ribbon or check when the latter is to be mounted on the section 20.

What I claim is:—

A holder for the purpose set forth comprising a retaining section consisting of a hollow body portion including a top, a side and a dish-shaped bottom formed with a central opening, said bottom being concavo-convex in cross section and a frusto-conical sleeve integral at its larger end with said bottom and arranged completely within the body portion and of a length to project beyond said bottom, the inner end of said sleeve being spaced

from the inner face of said top, and a supporting section consisting of a circular base and an integral stem extending through said sleeve into said body portion, said stem 5 formed of two portions of different diameters to provide a shoulder, that portion of smallest diameter integral concentrically with one face of said base and of less length than the portion of greatest diameter, said portion of 10 greatest diameter slotted to provide a series of resilient arms, and a triangular shaped

head integral with the free end of each arm and having its outer face curving outwardly and downwardly throughout from its apex to its base, said heads co-acting with the inner 15 edge of said means for securing the retaining section and supporting section together, and said shoulder and base co-acting to secure a check to said stem.

In testimony whereof, I affix my signature 20
hereto.

ALBERT C. FORTE.
